UNITED STATES PATENT OFFICE.

WILLIAM JOHN KENNEY, OF WILMETTE, ILLINOIS, ASSIGNOR TO UNDER-FEED STOKER COMPANY OF AMERICA, OF CHICAGO, ILLINOIS, A CORPORATION OF NEW JERSEY.

AUTOMATIC CLEANING MECHANISM FOR STOKERS.

1,196,870.

Specification of Letters Patent. Patented Sept. 5, 1916.

Application filed May 24, 1913. Serial No. 769,565.

To all whom it may concern:

Be it known that I, WILLIAM J. KENNEY, a citizen of the United States, residing at Wilmette, county of Cook, State of Illinois, have invented a certain new and useful Improvement in Automatic Cleaning Mechanism for Stokers, and declare the following to be a full, clear, and exact description of the same, such as will enable others skilled in the art to which it pertains to make and use the same, reference being had to the accompanying drawings, which form a part of this specification.

My invention has for its object to improve the mechanism by which furnaces are kept clean so as to make it possible to regulate the moving of the clinkers and ashes and their discharge in such a way as to secure the best results under all the working conditions.

A further object of my invention is to produce a simple and novel selective discharging mechanism for clinkers and ashes, by means of which the clinkers and ashes may be removed from one section without interfering with another section which may not perhaps be ready to be cleaned.

A further object of my invention is to simplify and improve the mechanical construction of dumping devices by means of which the clinkers and ashes are finally discharged from a furnace.

The various features of novelty whereby my invention is characterized will herein-after be pointed out with particularity in the claims; but, for a full understanding of my invention and of its objects and advantages, reference may be had to the following detailed description taken in connection with the accompanying drawings,

wherein:

Figure 1 is a horizontal section through a furnace equipped in accordance with my invention, a section being taken above the means for supporting and handling the fuel, 45 clinkers and ashes; Fig. 2 is a vertical longitudinal section taken on a plane lying at one side of one of the retorts in the furnace; Fig. 3 is an enlarged side view of one of the dumping members for the clinkers and 50 ashes; Fig. 4 is a section on an enlarged scale taken approximately on line 4-4 of Fig. 2; Fig. 5 is a view partly in plan and partly in section of the actuating mechanism for the cleaning and discharging mechanism; Fig. 6 is a front view of the mecha-

nism shown in Fig. 5; Fig. 7 is a section taken approximately on line 7-7 of Fig. 5; Fig. 8 is a view looking upwardly at the left hand side of Fig. 5; and Fig. 9 is a front view of the hand levers for controlling the connection between the cleaning and discharge mechanism and the power device, the reciprocating power-transmitting member being shown in section.

In the drawings I have illustrated my invention as applied to a furnace containing two retorts and, for the sake of brevity, the detailed description will be confined to this specific embodiment of my invention, although it will of course be understood the invention is not limited to this particular construction and arrangement.

Referring to the drawings, 1 represents a furnace in which are arranged the retorts 2 and 3 of an automatic under-feed stoker of a well known type. Between the retorts is a dead plate, 4, and similar dead plates 5 and 6 are placed between the retorts and the side walls of the furnace. Behind the dead plates and the retorts is a bridge wall, 7, this bridge wall being spaced apart from the rear ends of the dead plates and retorts so as to provide a passage, 8, through which the clinkers and ashes may be discharged. Fuel is fed into the retorts from suitable hoppers, 9 and 10, by means of suitable charging cylinders, 11 and 12, the fuel entering the front ends of the retorts and being fed rearwardly and upwardly; combustion beginning in the zones just below the tops of the retort; the retorts being provided with suitable twyer blocks, 13, around the tops thereof to supply air under pressure from the air chamber 14 beneath the retorts and dead plates. Each dead plate is provided with one or more rows of openings, 15, in which are pivoted dogs, 16; these dogs normally lying so that no part thereof projects above or, at least, considerably above the upper surfaces of the dead plates. The dogs of each longitudinal row are connected together by a bar, 17, lying below the dead plates and each bar, 17, is in turn connected to a crank arm, 18, projecting radially from a horizontal shaft, 19; the connection between the members 17 and 18 being conveniently in the form of an adjustable link, 20. When the shaft 19 is rocked it causes the noses of the dogs to be swung upward and rearward, breaking the clinkers from the twyer blocks and feeding

90

95

100

105

110

the entire mass overlying the dead plates toward the discharge passage.

In actual practice it very rarely happens that there is complete uniformity in the condition of the burning fuel and the clinkers and ashes at all points along and in the transverse line extending entirely across the furnace. Consequently any means which always discharges the clinkers and ashes simultaneously at all points across a furnace will not give the most efficient results. In accordance with one feature of my invention I have provided a selective discharging mechanism which will permit an accumulation of clinkers and ashes to be discharged from any one of a number of sections without disturbing the clinkers and ashes which have been delivered to the other sections. In the specific arrangement shown, I accomplish this by placing across the upper end of the discharge passage a sectional dumping shelf and providing means for operating one or more of the sections independently of the others. In the arrangement shown, the shelf is made in five sections, numbered in the drawings 21 to 25 respectively, each section lying directly behind one of the dead plates or behind one of the retorts. As will hereinafter be explained, either the section 21 or 22 may be actuated independently of the other. Similarly the section 24 may be actuated independently of the sections 23 and 25. Thus the clinkers and ashes directly behind either retort may be discharged without disturbing the clinkers and ashes being collected behind the other retort and behind the dead plates; the clinkers and ashes behind the dead plate 5 may be discharged without disturbing the accumulation behind the retorts or the other dead plates; or the clinkers and ashes behind the dead plates 4 and 6 may be discharged alone. Furthermore, either the section 24 or the sections 23 and 25 may be operated simultaneously with either of the sections 21 and 22. By this means the clinkers and ashes at any point or points from which it may be desirable to remove them may be discharged without disturbing the clinkers and ashes at other points where it may be better not to disturb existing conditions.

The sections of the dumping shelf are mounted loosely upon a horizontal shaft, 29, lying at the rear side of the discharge passage. In the arrangement shown, each shelf section has two separated hubs, 30 and 31, through which the shaft 29 passes. The hub 30 of each of the sections forms one member of a clutch. Splined to the shaft between each pair of hubs are clutch members indicated at 32 to 36 respectively, each of these clutch members being adapted to coöperate with one of the hub members

30 to clutch the corresponding section of the discharging shelf to the shaft. The clutch members 32 and 33 are engaged by a common actuating member, 37, so that both of these clutch members are moved simultaneously. The clutches of which the members 32 and 33 form part are oppositely disposed, however, so that when the member 37 is moved toward the left, as viewed in Fig. 4, the shelf section 21 is clutched to the shaft and the section 22 is left loose on the shaft. When the member 37 is moved toward the right past a neutral position, the shelf section 22 is clutched to the shaft while the section 21 is left free. In the same way, the clutch members 34, 35 and 36 are all engaged by a common actuating member, 38. The clutches of which the members 34 and 36 form part are similarly disposed and are adapted to clutch the shelf sections 23 and 25 to the shaft when the actuating member is moved toward the left. When the actuating member 38 is moved toward the right past a neutral position, the clutch of which the member 35 forms a part locks the shelf section 24 to the shaft, the sections 23 and 25 being left free. The member 37 extends out through the side wall of the furnace and is there connected to a suitable actuating arm or lever, 39. An actuating bar, 40, connected to the member 38 lies beside the member 37 and is connected at its outer end to a handle or lever, 41, similar to the handle or lever 39. By pushing in on either lever, the section of the dumping shelf corresponding to one of the retorts will be clutched to the shaft. By pulling either of the levers outwardly, the dumping member 21 behind one of the dead plates, or the dumping members 23 and 25 behind the other two dead plates will be clutched to the shaft, depending upon which of the handles or levers was operated. The shaft 29 may be oscillated at will by means of a connecting rod, 43, secured to one end of a crank arm, 44, projecting radially from the shaft; suitable operating means for the connecting rod being provided as will hereinafter be described.

I have found that the discharging of the clinkers and ashes requires more than a mere dumping shelf on which they are received by the cleaning mechanism and from the retorts. Sometimes a large piece of clinker partly overhangs the discharge passage but is prevented from dropping down when the shelf is actuated, either by reason of the manner in which its mass is disposed or by reason of the clinkers and ashes piled around the same and which have not yet reached the discharge passage. To insure satisfactory cleaning, a large overhanging clinker or mass of clinkers should be gotten out of the way so as not to interfere with

the clinkers and ashes which are to follow it. It is difficult to break or shear off a portion of a large clinker and therefore the presence of breaking or shearing means sometimes results in damaging the discharging mechanism because the clinker offers a greater resistance to disintegration than the discharging mechanism is designed to withstand.

10 In accordance with one feature of my invention I provide means for insuring the discharge of a large clinker which should be disposed of, in such a way that a positive discharge is effected without danger of straining the mechanism. I accomplish this by providing each section of the dumping shelf with an upwardly and forwardly curved portion, 45, arranged along the rear edge thereof; the radial distance from the 20 top of the member 45 to the axis of the shaft 29 being considerably less than the distance from this axis to the rear ends of the dead plates and retorts. Consequently, if a large 25 clinker should be projecting only slightly over the discharge passage when the dumping mechanism is actuated, the nose 49 will clear it and thus no strain will be placed on the mechanism. However, if the clinker projects so far that it should be gotten out 30 of the way before a succeeding dumping operation, then the member 45, while the shelf is in the act of dumping, will swing down on top of the clinker and will tilt it so as to cause it to drop of its own weight into 35 the discharge passage. In this way large clinkers will be removed positively whenever necessary without subjecting the discharge mechanism to the enormous stresses incident to breaking or shearing a clinker.

40 The dumping shelves are subjected to considerable wear and therefore in order to save the expense of replacing a whole section after a certain amount of wear has taken place, I provide each shelf with detachable 45 wearing plates which can readily be removed and replaced by others. This feature of my invention is best illustrated in Fig. 3. It will be seen that the dumping shelf with its curved projection is made in 50 skeleton form. Upon the flat portion of the shelf and along the front face of the projecting part 46 lies a detachable plate, 47, which may conveniently be provided near the front with a depending hook, 48, adapted 55 to engage under a shoulder, 49, on the shelf proper, the hook extending down through a slot, 50. The plate may also be provided with one or more ears, 51, adapted to project through a slot or slots, 52, in the 60 main portion of the shelf and be held against withdrawal by means of a pin or pins, 53, inserted through the same. On the rear side of the projecting portion, 46, of the shelf is a curved plate, 54, hooked at its upper front 65 end over the upper edge of the plate 47 as

indicated at 55 and having an ear, 56, which extends through a slot, 57, in the main portion of the shelf. A pin, 58, passing through the ear 56 prevents the withdrawal of the same. It will thus be seen that by removing 70 the pin 58 the plate 54 which forms the nose of the clinker pusher may be lifted out of position, so that this member may be removed and replaced quickly and conveniently. In the same way, the plate 54 being 75 out of the way, by simply removing a pin or pins 51, the plate 47 may be detached. Therefore, whenever one of the plates becomes worn, it can quickly be removed and be replaced by another without requiring the 80 services of a skilled mechanic and without wasting any part which is still in a useful condition. While I have referred to the plates 47 and 54 as extending across the entire width of a shelf section, it is of course 85 evident that these plates may be made narrower so that it will require two or more lying side by side to cover one of the sections.

It is desirable to actuate the cleaning 90 mechanism, that is the dogs, 16, and the discharging mechanism, that is the dumping shelves, without regard to each other; or, at least, without making it necessary to operate one whenever the other is operated. 95 It is furthermore desirable to permit either the cleaning mechanism or the discharging mechanism to be operated at will, so that either may be allowed to remain idle or be caused to operate, just as the conditions require. To this end I have provided a suitable power device, 60, which may conveniently be in the form of a steam cylinder and piston, together with means for connecting either or both the cleaning mechanism or the discharging mechanism thereto at will. In the arrangement shown, (see Figs. 2 and 3 to 9,) the horizontal shaft 19 has journaled thereon one end of an arm, 61, whose other end is hinged to the reciprocating power-transmitting bar or rod, 62, extending from the power device 60. Fixed to the shaft 19 beside the arm 61 is a depending arm, 63. On the lower end of the arm 63 is a suitable catch device which permits this arm to be locked to the power-transmitting rod so that as the rod reciprocates the shaft 19 is caused to oscillate, thus setting the cleaning mechanism into motion. In the arrangement shown, there 110 is hinged to the lower end of the arm 63 a bar, 64, having in the bottom thereof a notch, 65, adapted to receive a pin, 66, projecting laterally from the member 62. The free end of the bar 64 is connected to a suitable hand lever, 67. By moving the hand lever 67 in one direction, the bar 64 is raised so as to bring the notch therein clear of the pin 66. When the hand lever is moved in 115 the opposite direction, the bar 64 is dropped 120

125

130

so that the pin 66 is caught in the notch and the bar 64 thereafter reciprocates as a part of the power-transmitting rod 62. On the shaft 19 is loosely hung a third arm, 68, 5 the lower end of which is hinged to a bar, 69, similar to the bar 64 but lying on the opposite side of the member 62 from that on which the bar 64 is located. The bar 69 has in its under side a notch, 70, corresponding to the notch 65, the notch 70 being adapted to receive a pin, 71, projecting laterally from the power-transmitting member 62. The front end of the bar 69 is connected to a suitable hand lever, 72, similar 15 to the hand lever 67. By operating the hand lever 72, the arm 68 may be coupled to or uncoupled from the power-transmitting rod, as may be desired. The front end of the connecting rod 43 by means of which 20 the shaft 29 of the discharging mechanism is oscillated is connected to the arm 68 as indicated at 73. Consequently when the arm 68 is coupled to the power-transmitting device 62 the shaft 29 will be oscillated so 25 that whenever it is desired to actuate the dumping shelves it is only necessary to throw in the proper clutches in order to discharge the clinkers and ashes wherever and whenever desired.

30 It will thus be seen that I have provided an extremely flexible cleaning and discharging mechanism by means of which it is possible to feed the clinkers and ashes toward the discharge passage when and as desired and to effect the final removal of the clinkers and ashes in the most advantageous manner.

While, for the sake of brevity, I have illustrated and described only a single 40 stoker apparatus in which all of the various features are combined in a definite manner, I do not desire to be limited to the specific structural details illustrated and described or to an apparatus in which all of the various 45 novel features of my invention are incorporated; but I intend to cover all forms and arrangements which embody any one or more of the novel features, as will be evident from the terms employed in the definitions of my invention constituting the appended claims.

I claim:

1. In combination, a furnace, a support for fuel and ashes in said furnace, means for 55 moving the ashes toward one edge of said support, a sectional discharging mechanism for the ashes adjacent to said edge, a power shaft, and means for selectively clutching the sections of said discharging mechanism to said shaft.

2. In combination, a furnace, a support for fuel and ashes in said furnace, means for 60 moving the ashes toward one edge of said support, a sectional discharging mechanism for the ashes adjacent to said edge, an

actuator, and means for selectively connecting the sections of said discharging mechanism to said actuator.

3. In combination, a furnace, a retort within the furnace, supports for clinkers and 70 ashes beside the retort, a sectional discharging mechanism arranged beyond one end of the retort; an actuator, and means for connecting to the actuator either the sections of 75 said mechanism adjacent to said supports or adjacent to said retort or all of the sections.

4. In combination, a furnace, a retort in 80 said furnace, supports for clinkers and ashes beside said retort, and means at one end of 85 said retort and said supports for discharging the clinkers and ashes delivered at said end of the retort independently of the clinkers and ashes delivered at said end from the said supports.

5. In combination, a furnace, a retort in 90 said furnace, means for feeding fuel into one end of the retort, cleaning mechanism at the sides of the retort for receiving clinkers and ashes from the retort and moving 95 them in the direction of the length of the retort, and means for discharging the clinkers and ashes delivered from the other end of the retort and from said mechanism independently of each other.

6. In combination, a furnace, a retort in 100 said furnace, means for feeding fuel into one end of the retort, cleaning mechanism at the side of the retort for receiving clinkers and ashes therefrom and moving them 105 in the direction of the length of the retort, means for discharging the clinkers delivered from the other end of the retort, and other means capable of actuating independently of the aforesaid means for discharging the 110 clinkers and ashes delivered from said cleaning mechanism.

7. In combination, a furnace, a retort in 110 said furnace, means for feeding fuel into one end of the retort, cleaning mechanism at the sides of the retort for receiving clinkers and ashes flowing over the side of the retort and moving them in the direction of the other end of the retort, a sectional discharging 115 mechanism for clinkers and ashes, one section of said discharging mechanism receiving clinkers from the retort and another section receiving clinkers and ashes from said cleaning mechanism, and means for actuating one of said sections without actuating the remainder.

8. In combination, a furnace, a retort in 120 said furnace, dead plates beside the retort and adapted to receive clinkers and ashes therefrom, means for feeding fuel into one 125 end of the retort, a discharging device for clinkers and ashes adjacent to the opposite end of the retort, means for feeding the clinkers and ashes on the dead plates in the direction of the length of the retort, a sec- 130

- ond discharging device located adjacent to the dead plates and adapted to discharge the clinkers and ashes delivered from the dead plates, and means for actuating said devices independently of each other.
- 5 9. In combination, a furnace, a retort in the furnace, means for feeding fuel into one end of the retort, cleaning mechanism beside the retort for receiving clinkers and ashes therefrom and moving them toward the opposite end, a plurality of dumping plates arranged adjacent to the retort and to said mechanism at the latter end of the retort, and means for actuating said plates independently of each other.
- 10 10. In combination, a furnace, a retort in the furnace, means for feeding fuel into one end of the retort, cleaning mechanism beside the retort for receiving clinkers and ashes therefrom and moving them toward the opposite end, a plurality of dumping plates arranged adjacent to the retort and to said mechanism at the latter end of the retort, one of said plates extending substantially from one side of the retort to the other, and means for actuating said plates independently of each other.
- 15 11. In combination, a furnace, a retort in the furnace, cleaning mechanism beside the retort for receiving clinkers and ashes therefrom and feeding them toward one end of the retort, a shaft journaled at said end of the retort, a plurality of independent discharging devices loosely mounted on said shaft, means for turning said shaft, and selective means for clutching said devices to said shaft.
- 20 12. In combination, a furnace, a retort in the furnace, cleaning mechanism beside the retort, sectional cleaning mechanism at one end of the retort, one section registering with the retort and another section registering with the cleaning mechanism, and means for selectively actuating said sections.
- 25 13. An ash-discharging device for furnaces comprising a frame having an upwardly projecting inwardly curved portion at one end, a wearing plate detachably mounted on top of the frame and at the front side of said upwardly projecting portion, and a second wearing plate arranged on the outer side of said upwardly projecting portion and extending forwardly to the other wearing plate.
- 30 14. An ash-discharging device for furnaces comprising a frame having a flat portion and an upwardly-projecting curved member, a detachable wearing plate overlying the flat portion and the inner side of the curved member of said frame, and a second wearing plate detachably connected to and overlying the outer side of said curved member.
- 35 15. In combination, a furnace, a support for fuel and clinkers and ashes in said fur-
- nace, there being a discharge passage for clinkers and ashes at one end of said support, means for moving the clinkers and ashes toward said passage, and a discharge device comprising a plate extending across 70 said passage and pivotally supported on an axis remote from said support, said plate having thereon a part projecting upwardly above said support so located and proportioned that when the plate is swung down 75 said part swings toward said support but at all times remains separated from the retort by a considerable space.
- 40 16. In combination, a furnace having a support for fuel and clinkers and ashes and having also a discharge passage at one end of the support, means for feeding the clinkers and ashes toward said passage, a shelf extending across said passage and mounted to swing about a horizontal axis remote 80 from the support, said shelf having an upward projection whose extreme end is spaced from said axis a distance considerably less than the distance between said axis and said support and which extends above said support.
- 45 17. In combination, a furnace having a support for fuel and clinkers and ashes and having also a discharge passage at one end of said support, means for feeding the clinkers and ashes toward said passage, a shelf extending across said passage to receive the clinkers and ashes, said shelf being mounted to swing about a horizontal axis remote 85 from said support, a narrow portion of the shelf farthest removed from the said support being curved upwardly and in the direction of and to a point above said support, and means for swinging said shelf.
- 50 18. In combination, a furnace having a support for fuel and a discharge passage for clinkers and ashes, a shelf extending across said passage and mounted so as to swing about a horizontal axis near one side of the passage, said shelf having at the latter side 90 of the passage an upwardly-projecting part extending above the top of said support and considerably narrower than the passage, and means for swinging said shelf.
- 55 19. In combination, a furnace, a support for fuel and clinkers and ashes in said furnace, there being a discharge passage for clinkers and ashes at one end of said support, means for removing the clinkers and ashes toward said passage, and a discharge device comprising a plate extending across 100 said passage and pivotally supported on an axis remote from said support, said plate having a part in the vicinity of said axis projecting upwardly above the plane of said support and having a height considerably less than the distance between said support and said axis.
- 60 20. In combination, a furnace, a support for fuel and clinkers and ashes in said fur-

nace, there being a discharge passage for clinkers and ashes at one end of said support, means for moving the clinkers and ashes toward said passage, a discharge device comprising a plate extending across said passage and pivotally supported on an axis remote from said support, said plate having a part projecting upwardly above the plane of said support and curved forwardly toward said support to a point

spaced apart from said axis a distance considerably less than the distance between said support and said axis.

In testimony whereof, I sign this specification in the presence of two witnesses.

WILLIAM JOHN KENNEY.
